UNITED STATES PATENT OFFICE

MICHAEL WEHNER, OF KANSAS CITY, MISSOURI

DESIGN FOR A DIRECTIONAL SIGNAL FOR MOTOR VEHICLES

Application filed June 1, 1931. Serial No. 40,051. Term of patent 7 years.

To all whom it may concern:

Be it known that I, MICHAEL WEHNER, a citizen of the United States, residing at Kansas City, in the county of Jackson and State of Missouri, have invented a new, original, and ornamental Design for a Directional Signal for Motor Vehicles, of which the following is a specification, reference being had to the accompanying drawings, forming part thereof, in which—

Fig. 1 is a front elevation of the signal.

Fig. 2 is a plan view of the signal.

In practice right and left signals are employed with directional indicators such as Right and Left, respectively.

I claim:

The ornamental design for a directional signal for motor vehicles, as shown.

MICHAEL WEHNER.
